United States Patent Office

Des. 212,151
Patented Sept. 3, 1968

212,151

SIDING

Steve Costello, 236 Barrow St.,
Jersey City, N.J. 07302

Filed Nov. 14, 1967, Ser. No. 9,405

Term of patent 14 years

(Cl. D13—1)

FIG. 1 is an end view of a siding showing my new design, and FIG. 2 showing is a top perspective view thereof.

I claim:

The ornamental design for a siding, as shown.
